Primary Examiner — Karen S Acker*Assistant Examiner* — Andrew D Golson(74) *Attorney, Agent, or Firm* — Dinsmore & Shohl LLP(57) **CLAIM**

The ornamental design for a geometrical column unit, as shown and described.

DESCRIPTION

FIG. 1 is a perspective view of a geometrical column unit according to my new design;

FIG. 2 is a front view of the geometrical column unit of FIG. 1; the back view being a mirror image;

FIG. 3 is a right-side view of the geometrical column unit of FIG. 1; the left side view being a mirror image; and, FIG. 4 is a top view of the geometrical column unit of FIG. 1; the bottom view being a mirror image.

The geometrical column unit is intended to be stacked as a repeatable unit.
